UNITED STATES PATENT OFFICE.

HENRY T. GERDES, OF LEBANON, PENNSYLVANIA, AND ALFRED F. SCHUMANN, OF BROOKLYN, NEW YORK, ASSIGNORS TO HAUCK MANUFACTURING COMPANY, OF BROOKLYN, NEW YORK, A CORPORATION OF NEW YORK.

OIL BURNER.

Application filed July 31, 1923. Serial No. 654,839.

To all whom it may concern:

Be it known that we, HENRY T. GERDES and ALFRED F. SCHUMANN, citizens of the United States, and residents of Lebanon and Brooklyn, respectively, in the counties of Lebanon and Kings, respectively, and States of Pennsylvania and New York, respectively, have invented certain new and useful Improvements in Oil Burners, of which the following is a specification.

The invention relates to oil burning apparatus in which the oil is atomized, for example, by low pressure air and discharged for ignition in a highly atomized state thru a suitable tip.

It has for its object a burner having means for more efficiently atomizing the oil and mixing the same with a gaseous medium, more particularly in two stages; and to afford, also, a burner of simple and durable construction in which the flame is adjustable thru movement of the said tip; and wherein, furthermore, the oil supplying nozzle is conveniently removable for cleaning and so constructed as to be readily cleaned.

The nature of the invention, however, will best be understood when described in connection with the accompanying drawings, in which—

30 Fig. 1 is an elevation of the burner.

Fig. 2 is a plan thereof.

Fig. 3 is a longitudinal section thru the burner.

Fig. 4 is a fragmentary section of the sleeve for introducing the atomizing medium.

Similar characters of reference designate corresponding parts throughout the several views.

Referring to the drawings, the burner is shown to consist of a suitable casing having a vertically disposed chamber 10 through which the atomizing gaseous medium, as air under the requisite pressure, is to be supplied, the volume of same being controllable by a suitable valve as the butterfly valve 11 provided therein. The upper portion of the casing comprises a body 12 affording a horizontally disposed chamber which is open to the vertical chamber 10 and is provided with an inlet 13 and outlet 14 axially disposed therein. Fitting coaxially within the body 12 is a sleeve or tubular member 15 having openings 16 to afford communication with the chamber 12 and thru which the gaseous

atomizing medium may enter. This sleeve is secured to the inlet 13 and its forward end projects beyond the outlet 14, terminating in a constricted and flaring outlet 17. An intermediate portion of the sleeve is also constricted, as at 18, to form a Venturi nozzle in conjunction with the oil supply nozzle 20 which is mounted coaxially within said sleeve, the nozzle having an axial bore 21 extending from end to end and provided with radial outlets 22 at the Venturi end. The air velocity is consequently increased at this point, its atomizing effect enhanced and an intimate mixture therewith of the oil supplied thru the radial outlets 22 is secured. The bore of the nozzle is closed at this end preferably by a pipe plug 23; and, similarly, the opposite end of the bore is closed by a pipe plug 24 fitting in the head 25 of the nozzle. The head 25 serves also to seal the inlet 13 of the body 12 and is provided with a duct 26 communicating with the bore 21, the former having suitable means for outside connection to supply oil to the nozzle. By this expedient, the nozzle with head is conveniently removable; and by unscrewing the plugs 23 and 24 from the ends thereof, the bore is open throughout and may readily be cleaned when this becomes necessary.

Surrounding the forward end of the sleeve 15 and having a sliding fit with a portion of the same and with the body portion 12 to close substantially the outlet 14 of the latter, is an adjustable tip 30, tubular in form and having an opening 31 at its outer end coaxial with the flaring outlet 17, the wall of the tip and the outer end of the sleeve being separated and forming a tapering annular space between the same. The tip, moreover, is provided with openings 32 to afford communication between the interior of the body portion and the said tapering annular space so that the gaseous atomizing medium may also be supplied thereto. By disposing these openings 32 as well as the openings 16, respectively in the walls of the tip and sleeve, at suitable angles, the gaseous medium may be introduced to the interiors of the said sleeve 15 and tip 30 with a swirling motion which greatly facilitates the atomization and mixture of the oil discharged thru the radial openings 22. The intimate mixture of oil and air produced is

carried forward by the air delivered thru the annular space to the outlet 31 of the tip where it is further atomized and mixed and discharged for ignition with a blowing effect, the swirling motion heretofore referred to being also imparted to the flame.

Furthermore, to vary the character and extent of the flame discharged at the opening 31, the tip 30 is arranged to be axially 10 adjustable with respect to the flaring outlet 17, that is to say, the tip is arranged to slide in a bearing therefor formed between the sleeve 15 and the outlet 14 of the body portion. To effect this reciprocation of the tip, 15 a yoke 35 is arranged over the burner apparatus with its arms at either side thereof, and the ends of said arms are secured to the tip 30 at diametrically opposed points. Thru an opening 36 in the back of the yoke 20 is inserted a stud 37 which is threaded into the head 25 of the oil nozzle, said stud carrying a collar 38 within the yoke; and at its outer end a hand wheel 39 is adapted to shoulder against the back of the yoke, so 25 that in turning the said hand wheel, the yoke is correspondingly advanced or retracted to adjust the tip 30. In order to limit the extent of the reciprocation, the arms of the yoke are provided with open 30 notches or slots 40 in the upper edges thereof and into which fit corresponding pins 41 secured in the body portion 12, the same acting as stops thru engagement with the respective sides of the notches.

35 We claim:—

1. An oil burner, comprising a casing provided with an inlet for a gaseous medium, a sleeve longitudinally arranged therein and in communication with the interior of the 40 casing, said sleeve having an axial outlet and a constricted intermediate portion, the portions of the sleeve immediately in advance and succeeding said constricted portion flaring in opposite directions, an oil supply nozzle mounted coaxially therein and having radial outlets in proximity to the constricted intermediate portion of the sleeve.

2. An oil burner, comprising a casing provided with an inlet for a gaseous medium, a sleeve longitudinally arranged therein and in communication with the interior of the casing, said sleeve having an axial outlet and a constricted intermediate portion, the 55 portions of the sleeve immediately in advance and succeeding said constricted portion flaring in opposite directions, an oil supply nozzle coaxially mounted therein and provided with a head substantially closing the casing at one end, said nozzle having radial outlets at the opposite end for delivering oil into the sleeve substantially at the constricted intermediate portion of the sleeve.

3. An oil burner, comprising a casing pro-

vided with an inlet for a gaseous medium, a sleeve arranged in the casing and communicating with the interior thereof, said sleeve having an axial outlet and a constricted intermediate portion, the portions of the 70 sleeve immediately in advance and succeeding said constricted portion flaring in opposite directions, a removable oil supply nozzle axially mounted therein and provided with radial outlets in proximity to the said constricted intermediate portion, said nozzle being bored longitudinally thru, and removable plugs at the respective ends of the nozzle.

4. An oil burner, comprising a casing provided with an inlet for a gaseous medium, a sleeve arranged in the casing and communicating with the interior thereof, said sleeve having an axial outlet and a constricted intermediate portion, the portions of the 85 sleeve immediately in advance and succeeding said constricted portion flaring in opposite directions, a removable oil supply nozzle axially mounted therein and provided with radial outlets in proximity to the said constricted intermediate portion, said nozzle being bored longitudinally thru, removable plugs at the respective ends of the nozzle, and a movable tip mounted about 90 said sleeve outlet and providing an annular chamber thereabout, the same communicating with the interior of the casing and having an outlet beyond the outlet of the said sleeve.

5. An oil burner, comprising a casing provided with an inlet for a gaseous medium, a sleeve arranged in the casing and communicating with the interior thereof, said sleeve having an axial outlet and a constricted intermediate portion, the portions of the sleeve immediately in advance and succeeding said constricted portion flaring in opposite directions, an oil supply nozzle coaxially mounted therein having radial outlets in proximity to the said constricted 105 intermediate portion in advance of the outlet of said sleeve, a movable tip mounted about said sleeve outlet and providing an annular chamber thereabout, the same communicating with the interior of the casing and having an outlet beyond the outlet of said sleeve, a yoke having its arms secured to diametrically opposite points of the tip, a stud 110 screwed into the casing end and passing thru the yoke to engage with same in one direction of rotation, and a collar on the stud to engage with said yoke in the other direction, whereby on rotating the screw the tip may be reciprocated axially, the arms of said yoke being notched, and pins secured 115 in the casing and fitting the notches of the arms to restrict the extent of reciprocation of the yoke.

6. An oil burner, comprising a casing provided with an inlet for a gaseous medium, a 120

- sleeve arranged in the casing and communicating with the interior thereof, said sleeve having an axial outlet and a constricted intermediate portion, an oil supply nozzle coaxially mounted therein having radial outlets in proximity to the constricted intermediate portion of said sleeve, said nozzle being bored longitudinally thru, removable plugs at the respective ends of the nozzle, a movable tip mounted about said sleeve outlet and providing an annular chamber thereabout, the same communicating with the interior of the casing and having an outlet beyond the outlet of the said sleeve, a yoke having its arms secured to diametrically opposite points of the tip, a stud screwed into the casing end and passing thru the yoke to engage with same in one direction of rotation, and a collar on the stud to engage with said yoke in the other direction, whereby on rotating the screw the tip may be reciprocated axially, the arms of said yoke being notched, and pins secured in the casing and fitting the notches of the arms to restrict the extent of reciprocation of the yoke.
7. An oil burner, comprising a casing provided with an inlet for a gaseous medium, a sleeve longitudinally arranged therein and in communication with the interior of the casing, said sleeve having an axial outlet and a constricted intermediate portion, the portions of the sleeve immediately in advance and succeeding said constricted portion flaring in opposite directions, an oil supply nozzle mounted coaxially therein and having radial outlets in proximity to the constricted intermediate portion of the sleeve, and a movable tip mounted about said sleeve outlet and providing an annular chamber thereabout, the same communicating with the interior of the casing and having an outlet beyond the outlet of said sleeve.
- 10 15 20 25 30 35 40 45

Signed at Brooklyn in the county of Kings and State of New York this 25th day of July A. D. 1923.
